UNITED STATES PATENT OFFICE.

GEORGE H. SARGENT, OF NEW YORK, N. Y., ASSIGNOR TO SARGENT & CO.,
OF NEW HAVEN, CONNECTICUT.

TRANSOM-LIFTER.

SPECIFICATION forming part of Letters Patent No. 324,170, dated August 11, 1885.

Application filed June 1, 1885. (No model.)

To all whom it may concern:

Be it known that I, GEORGE H. SARGENT, of New York, in the county of New York and State of New York, have invented a new Improvement in Transom-Lifters; and I do hereby declare the following, when taken in connection with accompanying drawings, and the letters of reference marked thereon, to be a full, clear, and exact description of the same, and which said drawings constitute part of this specification, and represent, in—

Figure 1, a front view of the lifter as applied to the jamb and transom; Fig. 2, a side view of the same; Fig. 3, a vertical section through the worm-disk and rack enlarged; Fig. 4, an inside view of the disk enlarged.

This invention relates to an improvement in the device applied to the jamb of a door-opening for connection with the transom over the door and by which the transom may be opened or closed; and the invention consists in the construction hereinafter described, and particularly recited in the claims.

A represents the jamb of the door to which the lifter is applied, and B the transom hinged above, as at a; C, the adjusting-rod, which is arranged in suitable bearings, b b, and so as to move freely up and down therein. From the transom an arm, D, extends outward, and from the outer end of this arm to the rod C is a connecting-link, E, and so that by raising the rod C the transom will be opened, as indicated in broken lines, Fig. 2, or drawing the rod downward the transom will be closed, as indicated in Figs. 1 and 2.

At some point on the rod, and preferably at its lower end, I construct it with a series of teeth transversely across it in the form of a toothed rack, F.

G is a worm, (here represented as a flat disk,) having a worm or spiral shaped rib, d, upon its under face. This disk is arranged in a bearing, H, outside the rack, the bearing supported independent of the rack and so as to hold the disk in a position inclined to the rack, as indicated in Fig. 3, so that only that part of the worm on one side of the center will engage the teeth.

To the disk a suitable handle, I, is attached, and to which a person desiring to adjust the

transom may readily apply the hand and impart rotation to the worm-disk G. By turning the disk in one direction the action of the worm-rib d on the rack is to raise the rod and open the transom; turned in the opposite direction it is to draw the rod downward to close the transom.

The bearing-point of the teeth of the rack on the worm is in a radial line through the center; hence the bearing has no tendency to cause the worm-disk to rotate; therefore at whatever point the rod may stand it is firmly locked by the worm and can only be moved by the rotation of the worm, and because of the spiral or worm-like shape of the rib suitable force may be applied in closing the transom so as to bring it to a firm bearing in its closed position, and the same power is applied in opening the transom should it stick when closed, and at whatever position the transom may be it will be firmly held by the worm through the rack against any possible influence applied directly upon it.

The power of the worm upon the rack is so great that very little force applied to rotate the worm will impart corresponding movement to the rod and transom.

By this construction all liabilities to accident in opening and closing the transom are avoided, and many obvious difficulties attending the use of transom-lifters provided with clamping devices are also avoided.

Any of the known connections between the vertical sliding rod and the transom may be employed to make connection between the rod and transom. I therefore do not wish to limit my invention to the particular connection which I have shown and described.

It will be observed that this device is applicable to a transom hung at the top or bottom or pivoted at the center, and is also applicable to opening and closing skylights, traps, &c., which are hinged or pivoted, and is also applicable to sliding devices—such, for illustration, as a window-sash, the rod being connected directly to the sash, so that the up-and-down movement of the rod will impart a corresponding up-and-down movement to the sash. I therefore do not wish to be understood as limiting the invention to the operation of

transoms, or to the operation of a sash or other device hinged or pivoted.

I am aware that a pinion with a worm has been employed to operate swinging sash, as for 5 ventilators; but in such case a horizontal rock-shaft is required, from which an arm extends radially, and from which arm a connecting-rod is hung to the sash, and so that by rotating the worm a rocking movement is imparted 10 to the shaft, which rocking movement of the shaft imparts corresponding swinging movement to the sashes engaged with the shaft. I do not, therefore, wish to be understood as claiming, broadly, the employment of a worm- 15 gear to operate a swinging sash.

I claim—

1. The herein-described improvement in transom-lifters, consisting in the lifting-rod constructed with a toothed rack, F, combined 20 with a worm supported in a bearing for rotation, said worm adapted to work in the teeth of the said rack, and whereby, under the rotation of the worm, vertical movement is im-

parted to the said rod, and with a connection between said rod and transom, whereby vertical movement of the rod will impart opening or closing movement to the transom, substantially as described. 25

2. In a transom-lifter, the combination of the vertical rod, C, constructed with a toothed rack, F, the disk G, constructed with a spiral or worm-like rib, d, upon its inner face, and arranged in a bearing outside the said rack, the axis of the bearing inclined to the plane of the rack and so that the rib on the disk may work 30 in the teeth of the rack, the said disk provided with a suitable handle for imparting rotation to it, and connection between said rod and the transom, whereby vertical movement imparted to the rod will be communicated to 35 the transom, substantially as described. 40
